Attorney.

UNITED STATES PATENT OFFICE

ALFRED LEWIS AND HARRY ALPHONSE WIDMER, OF LONDON, ENGLAND, ASSIGNEES
TO THE TUCK-TITE LOCK & FASTENER COMPANY LIMITED, OF LONDON, ENGLAND,
A COMPANY OF GREAT BRITAIN AND IRELAND

FASTENING

Application filed May 16, 1928, Serial No. 278,268, and in Great Britain March 21, 1928.

The present invention relates to improvements in those spring fastenings described in patent specifications Nos. 1,590,400 dated 29th June, 1926, and 1,642,598, dated 13th 5 September, 1927, in which a bolt attached to one member of the article to be fastened is fitted with a pivoted engaging latch controlled by an independent spring and adapted to be pushed under a bridge attached to the other 10 member of the article and to be pressed down against the influence of the spring to allow of the tab or bolt being released from the bridge. These spring fastenings have proved very satisfactory in use and have been adapted for 15 widely different purposes. In addition to use as fastenings for leather and other containers experience has shown that fasteners of this character can be usefully applied to doors and lids of all kinds and sizes, wearing apparel, 20 coverings for motor vehicles and aircraft and for every purpose where a quick and at the same time efficient fastening is essential or desirable.

For many purposes it is desirable to employ 25 a fastening which will automatically move into the disengaged position when the catch is released in the manner generally employed in fastenings for suit cases and other articles of this nature.

The present invention is designed to provide in a fastening of the character described 30 an automatic release from the bridge when the pivoted latch is pressed down below the level of the bridge.

The present invention provides a fastening 35 of the character described, in which the bolt carrying the pivoted latch is free to move in a guideway and is adapted to withdraw automatically from the bridge when its latch is pressed down to release the fastening.

Our invention is shown by way of example in the accompanying drawings, in which—

Figure 1 is a perspective view of the members of the fastening according to the present 45 invention shown with the sliding bolt apart from the bridge.

Figure 2 is a plan view of the fastening with the members together but with the bolt with- 50 drawn from the bridge.

Figure 3 is a section on the line A—B of Figure 2.

Figure 4 is a plan view of the fastening fitted with a lock and with the bolt in engagement with the bridge. 55

Figure 5 is a section on the line C—D of Figure 4, and

Figure 6 shows a detail view of an alternative form of limiting stop and guideway therefor. 60

Referring now to the drawings, the bolt 1 is provided with a recess 2 in which is pivoted a latch 3 provided with a spring 4 normally urging it upward into the position shown more particularly in Figures 1, 3 and 5 the 65 upward position being limited by the projecting lip 5. In the fastened position the bolt is pushed through the bridge 6 and held by the latch 3. This construction is substantially the same as that described in our earlier 70 Patents 1,590,400 and 1,642,598. In order to allow of an instantaneous automatic release from the bridge when the hinged engaging latch is pressed down below the level of the 75 bridge 6, the bolt 1 is free to slide in a U-shaped guiding plate 7 screwed or otherwise attached to a member of the article to be fastened such as for instance the lid of a leather trunk or case and is controlled by spring means tending to hold the bolt at the closed 80 end of the guideway. The tension springs 8 shown in Figures 3 and 5 connecting the transverse centre wall 18 of the bolt with the rear end of the guideway have proved satisfactory for the purpose in view, but it should be 85 understood that other forms of spring control may be employed to give the desired result. In the construction shown a limiting stop, such as the stop formed by the lip 9 sliding in the channel 19, is necessary to prevent the bolt member 1 from being drawn entirely out of the guideway 7. If the fastening forming the present invention is applied to 90 those forms of suit case which are expansible, it is desirable to have adjustable limiting stops to allow of varying the extreme forward movement of the bolt 1 in the guideway 7, to agree with the degree of expansion of the 95 case to which the fastener is applied. Such a variable limiting stop may be provided by 100

spring controlled buttons 11 as shown for example in Figure 6, in the sides of the bolt adapted to engage after a predetermined movement in one or other of the spaced apart openings 12 in the sides of the guiding plate 7. In order that the sliding bolt may be moved conveniently under the bridge 6 the bolt is provided with a manipulating handle. The member 10 shown in the drawings provides 10 such a handle in a form which is in keeping with the bridge 6 when the latch 3 is in engagement with said bridge and the parts are adjacent. The new fastening is particularly suitable for certain types of doors such as for 15 instance bedroom or bathroom doors. When so used the bolt forms a door bolt which is normally out of engagement and when in the locked position can be instantaneously released.

20 In Figures 1, 4 and 5, we show the application of a lock to the fastening. The construction differs from that described in patent specification 1,642,598 in that the lock is arranged beneath the latch 3 and its bolt 14 25 projects under the lip 5 of the shoulder 3 when in the locked position as shown in Figure 5.

What we claim is:—

1. A fastening for a container comprising a 20 guideway mounted on one member of the container, a bridge mounted on the other member of said container in proximity to said guideway, a bolt mounted in and free to move in said guideway and provided with a latch 25 adapted to be depressed when passing under said bridge and spring means adapted to withdraw said bolt from said bridge when the latch is positively pressed down below the level of the bridge.

2. A fastening for a container comprising a guideway mounted on one member of the container, a bridge mounted on the other member of the container in proximity to said guideway, a bolt mounted in and free to move 45 in said guideway provided with a latch adapted to be depressed when passing under said bridge, spring means adapted to withdraw said bolt from said bridge when said latch is positively pressed down below the 50 level of the bridge and means for limiting the forward movement of said tab bolt in said guideway.

3. A fastening for a container comprising a 55 U-shaped guide plate mounted on one member of the container, a cover plate at the rear end of said guide plate, a bridge mounted on the other member of the container in proximity to said guide plate, a bolt mounted in and free to move in said guide plate and provided with a latch adapted to be depressed 60 when passing under said bridge, spring means adapted to withdraw said bolt from said bridge when said latch is positively pressed down below the 65 level of the bridge and a lip at the rear end of said bolt

projecting into a channel in the cover plate of said U-shaped guiding plate and adapted to co-act with the closed end of said channel to limit the forward movement of said bolt.

4. A fastening for a container comprising a guideway mounted on one member of the container, a bridge mounted on the other member of said container in proximity to said guideway, a bolt mounted in and free to move in said guideway and provided with a latch 70 adapted to be depressed when passing under said bridge and a tension spring connecting the transverse centre wall of said bolt with the rear end of said guideway and adapted to withdraw it from said bridge when the latch 75 is positively pressed down below the level 80 of the bridge.

5. A fastening for a container comprising a U-shaped guide plate mounted on one member of the container, a cover plate at the rear end of said guide plate a bridge mounted on the other member of the container in proximity to said guide plate, a bolt mounted in and free to move in said guide plate and provided with a latch adapted to be depressed when 85 passing under said bridge, tension springs connecting said bolt with the rear end of 90 U-shaped guide plate and adapted to withdraw it from said bridge when said latch is positively pressed down below the level of 95 the bridge and a lip at the rear end of said bolt projecting into a channel in the cover plate of said U-shaped guide plate and adapted to co-act with the closed end of said channel to limit the forward movement of said 100 bolt.

6. A fastening for a container comprising a guideway mounted on one member of the container, a bridge mounted on the other member of said container in proximity of 105 said guideway, a bolt mounted in and free to move in said guideway and provided with a latch adapted to be depressed when passing under said bridge and a lock mounted in said bolt below said latch having a lock bolt which when shot projects beneath the lip of 110 said shoulder and retains it in its uppermost position, and spring means adapted to withdraw said bolt from said bridge when the latch is positively pressed down below the 115 level of the bridge.

7. A fastening for a container comprising a U-shaped guide plate mounted on one member of the container, a cover plate at the rear end of said guide plate, a bridge mounted on the other member of the container in proximity to said guide plate, a bolt mounted in and free to move in said guide plate and provided with a latch adapted to be depressed 120 when passing under said bridge, tension springs connecting said bolt with the rear end of the U-shaped guide plate and adapted to withdraw it from said bridge when said latch is positively pressed down below the 125 level of the bridge, a lip at the rear end of 130

said bolt projecting into a channel in the cover plate of said U-shaped guide plate and adapted to co-act with the closed end of said channel to limit the forward movement of
5 said bolt and a lock mounted in said bolt below said latch having a lock bolt which when shot projects beneath the lip of said latch and retains it in its uppermost position.

In testimony whereof we have signed our
10 names to this specification.

ALFRED LEWIS.

HARRY ALPHONSE WIDMER.
